UNITED STATES PATENT OFFICE.

JOHN W. PERRY, OF WHEELING, WEST VIRGINIA.

SHEET-HEATING FURNACE.

Application filed May 20, 1927. Serial No. 193,014.

This invention relates to sheet or plate heating furnaces and has for its objects the provision of a novel furnace of this class in which the sheets are mechanically handled and piled whereby an even heating and soaking of the sheets results.

Another object is to provide a furnace having the novel sheet handling mechanism hereinafter described and illustrated in the accompanying drawings.

In the drawings—

Figure 1 is a sectional plan of a heating furnace constructed in accordance with this invention.

Figure 2 is an end elevation thereof.

Figure 3 is a longitudinal sectional elevation on the line III—III of Figure 1.

Referring more particularly to the drawings, the letter A designates the furnace as a whole, which is provided with a combustion chamber 2 and heating chamber 3. The heating chamber 3 has a heating floor 4 and a stacking and soaking floor 5. The stacking floor 5 is approximately six inches lower than the heating floor 4 so that the sheets will fall one on top of the other when pushed or fed from the heating floor onto the stacking floor, thereby forming stacks.

The front or entering side of the heating chamber 3 is provided adjacent one end with an entering opening 6 through which the sheets to be heated are fed onto the heating floor 4, and an exit opening 7 is provided in the front side of the heating chamber 3 adjacent the opposite end and in line with the stacking and soaking floor 5, through which the heated and soaked stacks of sheets are discharged from the furnace.

The furnace as a whole is above the floor level of the mill in which it is installed and an elevator platform 8 is provided for elevating or lifting the sheets up to the level of the heating floor 4.

The platform 8 is carried by a post 9 which is reciprocably mounted in a hollow plunger 10 of a fluid pressure cylinder 12 and normally held in its extended position by a coil spring 13. A stop 14 is provided on the furnace adapted to be engaged by lugs 15 on the platform 8 to stop the platform at a position where its top face is on a line with the heating floor 4.

The places or sheets are adapted to be fed into the heating chamber 3 by a pair of

push-rods 16 which have their free ends supported on the heating floor 4 and their other ends pivotally secured to a lever 17 secured to a rock shaft 18. The shaft 18 is provided with a crank lever 19 which carries an operating lever 20. The lever 20 is pivotally suspended from the lever 19 and is adapted to be engaged by a rigid arm 21 carried by the plunger 10 and to be raised by the arm 21 to cause the lever 19 to rock the shaft 18 and operate the rods 16.

The rods 16 are provided with a sheet engaging lug 25 adjacent their rear ends and a second sheet engaging lug 26 at their forward or free ends. The lugs 25 are adapted to engage and feed the sheets from the platform 8 into the heating chamber 3 while the lugs 26 are adapted to engage the first sheet simultaneously with the engagement of the lugs 25 with a second sheet so as to advance the first sheet transversely across the heating floor 4 as the second sheet is entered.

A three-way valve 22 is provided for controlling the flow of fluid to the cylinder 12 and is provided with levers 23 and 24 for operating the valve. The lever 23, when tripped, will open the valve to admit fluid under pressure to the cylinder 12 and the lever 24, when tripped, will open the cylinder to the atmosphere to permit fluid to escape from the cylinder and lower the platform, 8.

In operation, when the platform 8 is in its lowermost position, which is in line with the floor, the operator will slide a sheet or pack of sheets onto the platform 8 and the sheet or pack of sheets will engage and trip the lever 23, thereby admitting fluid to the cylinder 12 and raising the plunger 10, post 9, and platform 8 until the lugs 15 on the platform 8 engage the stop 14 on the furnace. The platform will then remain stationary while the plunger 10 will continue to rise, causing the arm 21 to engage the lever 20 and rock the shaft 18 which will in turn operate the levers 17 and rods 16 to feed the sheet or pack through the opening 6 and onto the heating floor 4.

As the plunger 10 continues to advance, the platform 8 is permitted to remain stationary due to the compression of the spring 13. When the plunger 10 has reached the end of its travel the lever 24 of the valve is adapted to be tripped by a stop 28 on the plunger 10 so as to open the cylinder 12

to the atmosphere and permit the plunger 10 and the elements operated thereby to return to normal position, ready to receive another sheet or pack of sheets.

5 When the second sheet is fed onto the heating floor 4 and the first sheet advanced, the two sheets are adapted to be moved longitudinally along the heating floor 4 by pushers 29 a distance sufficient to permit a 10 second pair of sheets to be entered and after the second pair of sheets are entered the two pairs will be pushed longitudinally along the heating floor, etc., this operation being repeated until the sheets are pushed off the 15 floor 4 and onto the stacking floor 5 where they will form stacks B.

The pushers 29 are slidably mounted on elevating guide members 30 which normally support the pushers in slots below the level 20 of the heating floor 4 so as not to interfere with the sheets being fed into the furnace. The guides 30 are connected by links 31 to reciprocating rods 32, which rods are connected by links 33 to levers 34 carried by 25 a rock shaft 35. The shaft 35 is provided with a crank lever 36 which is connected to the plunger rod 37 of a fluid pressure cylinder 38.

30 The pushers 29 are provided with sheet engaging lugs 39 which are spaced so as to engage the several sheets to be fed longitudinally along the heating floor 4.

The pushers are connected at their rear ends by links 40 to rocker arms or levers 41 carried by a rock shaft 42, which shaft is provided with a crank arm or lever 43. The lever 43 is in turn connected by a link 44 with the plunger rod 45 of a fluid pressure cylinder 46.

40 A treadle operated four-way valve 47 is provided to be operated by the operator to admit fluid under pressure to the cylinder 38.

When the operator desires to move the sheets or packs of the furnace forwardly, 45 he will tramp on the treadle operated valve 47 so as to admit fluid under pressure to the cylinder 38 and thus raise the guides 30 and pushers 29 so that the lugs 39 will be elevated sufficiently to engage the sheets. 50 When the plunger of the cylinder 38 has reached a predetermined point it will uncover a port 48 which is connected to the cylinder 46 so that fluid under pressure will then be admitted automatically to the cylinder 46 and cause the pushers 29 to move forwardly and push the sheets longitudinally of the heating floor 4. The floor 4 is adapted to contain two rows of three sheets from end to end and when the two rows of 55 sheets are completed, further operation of the pushers 29 will push the foremost plates onto the stacking and soaking floor 5 where they will be stacked or piled in two separate piles, forming stacks.

60 The length of time necessary for the

sheets to be moved through the furnace is sufficient to heat them and the time elapsing before the stacks are formed is sufficient to permit the stacks to soak whereby all the sheets will be evenly and thoroughly heated. 70

The stacking floor 5 is provided with a pair of rails 50 on which the stacks of sheets are supported, and which also serve to facilitate the movement of the stacks of sheets out of the furnace. 75

A pushing ram 51 extends through the rear side wall of the furnace in line with the stacks B of sheets on the stacking floor and is adapted to be reciprocated by a fluid pressure cylinder 52. A four-way valve 80 53 having an operating lever 54 is provided for controlling the flow of fluid under pressure to the cylinder 52.

After the stacks B of sheets are heated and soaked the operator will operate the 85 valve 53 to admit fluid to the cylinder 52, which will move the ram 51 into the furnace and push the stacks of sheets out of the exit opening 7. The operator will then reverse the operation of the valve 53 to 90 return the ram to retracted position.

The sheets discharged from the furnace will be heated thoroughly and ready for further mill operation.

While I have shown and described one 95 specific embodiment of my invention it will be understood that I do not wish to be limited thereto since various modifications may be made without departing from the scope of my invention, as defined in the appended 100 claims.

I claim:

1. A heating furnace for sheets and plates, comprising a heating chamber, means for feeding at least two sheets transversely into said heating chamber in spaced relation, means for simultaneously feeding said sheets longitudinally of said heating chamber a distance equal to the width of said sheets with a step by step movement, 110 said first named feeding means being adapted to be operated between each of the step movements of said second named means so as to feed other sheets into the path of said second named means and immediately 115 back of the sheets previously fed into said chamber thereby forming two rows of sheets, and said second named means being adapted to feed said rows of sheets longitudinally of said chamber, a stacking floor 120 in said chamber at a point below the main level of said heating chamber, said second named feeding means being adapted to feed the sheets of said rows of sheets successively onto said floor forming stacks, and mechanical means for feeding said stacks of sheets from said stacking floor.

2. In a heating furnace for sheets and plates, having a heating chamber of a width and length sufficient to accommodate 130

- a plurality of sheets, said heating chamber being provided with the usual inlet and outlet openings, means for feeding the sheets into said furnace, said means comprising a vertically movable receiving platform adapted to be moved from the floor level upwardly to the level of the inlet opening in said heating chamber, a fluid pressure cylinder for raising and lowering said platform, means operable by the sheets as said sheets are positioned on said platform for controlling the operation of said cylinder, at least one feeding arm for moving the sheets transversely from said platform into said heating furnace, and means operable by said cylinder for operating said arm after said platform has been raised to the level of said inlet opening in said chamber.
3. A heating furnace for sheets and plates, comprising a heating chamber having a main heating floor and a stacking and soaking floor at a lower level than said
- heating floor, means for feeding at least two sheets into said heating chamber transversely of said heating floor, one in advance of the other, and other means for feeding said sheets longitudinally of said heating floor and onto said stacking and soaking floor, whereby successive sheets will be stacked, one on top of the other, said means comprising a plurality of reciprocating bars normally maintained below the level of said heating floor, sheet engaging lugs on said bars, means for raising said bars so that said lugs will engage the sheets on said heating floor, a manually operated control for said means, and other means for reciprocating said bars to move said sheets longitudinally of said heating floor, said last named means being controlled by bar raising means.

In testimony whereof, I have hereunto signed my name.

JOHN W. PERRY.
